1 Claim. (Cl. 260—146)

This invention relates to electric power switches having stationary and movable contact pieces, and has particular reference to an improved arc quenching means.

It is known to improve certain characteristics and properties of a switch, such as its freedom from arcing-back, with the aid of forced fluid flow. For example, a pump piston moving with the contact pin can produce a fluid flow which washes the tip of said pin. Another known possibility is the injection of the arc quenching fluid into the extinction chamber, by a displacement brought about by the moving pin itself. Pump pistons provided with a special drive mechanism are also used for this purpose. A further method consists in producing an auxiliary arc for building up the pressure, whereby a fluid flow aimed at the principal arc may be attained. The last-mentioned method has the disadvantage that it depends on the intensity of the arc-current. However, the requirements of modern switch-gear, such as freedom from arcing-back when switching capacitive currents on and off, call for a current more or less independent of the size of the switch-off current. The means operating with pistons are of relatively simple construction and rugged in operation. They, however, have the disadvantage that only one of the contact pieces is washed by the fluid current. It is, however, of great advantage for arc extinction that both arc bases be washed by the fluid. This has been unequivocally corroborated by theoretical and experimental investigations. The process of double circumflow may be realized in cases where the fluid is held ready under pressure at all times, such as in air-blast circuit-breakers. Washing of both contact pieces then is only a question of the proper arrangement of the quenching elements. To such end, however, an additional storage means is required which always has to make available the requisite quantity of pressurized fluid, even when not actuating the switch. In such case, however, the guarantee that the quenching capacity of the switch is maintained at all times, is substantially smaller than in the case of follow-up pistons and the like.

The deficiencies of the known means of this type may be avoided by providing, in accordance with the teachings of the present invention, two concentric insulating tubes extending in direction of the switch-rod path. The gap between these two tubes leads to an annular nozzle in the vicinity of a pair of stationary contact pieces, and said gap has a further communication to the interior of the extinguishing means in the vicinity of a pair of movable contact pieces which cause at least two fluid currents.

The advantage of the invention resides in the fact that the two pairs of stationary and movable contact pieces are washed by fluid without need for any additional storage means, and that the space between the stationary

2

and the movable contact pieces is subjected to a fluid current which is adjusted to the quenching conditions.

Forms of the invention are shown, by way of example, in the drawing, in which:

FIG. 1 shows a first form in vertical section; FIG. 2 illustrates schematically and on a much larger scale the position of the movable contact or burning pin shortly after separation of the metallic current path, i.e. shortly after creation of an arc; FIG. 3 is similar to FIG. 2 showing the lower position of the contact pin and contact head; FIG. 4 depicts a second form of the invention in a manner similar to FIG. 1; FIG. 5 shows a third form with a different nozzle contact piece; and FIG. 6 illustrates a fourth form with a pair of movable contact pieces affording an improved guiding of the fluid along the burning contact pin. Like parts are designated by the same numerals throughout the drawings. All the arrangements shown are sections of a complete switchgear unit. The invention may be used with gaseous and liquid quenching agents, and for low and high-tension switches.

In FIG. 1 a flange provided with a terminal or point of current supply 2 is screwed to the upper housing 1. To said flange is secured a metallic sleeve 3 which holds the exterior insulating tube 4. In the latter is disposed an intermediate tube 5 also made of insulating material. The tube 5, together with an interior insulating tube 6, forms a plurality of channels 8 and between these tubes. This communication terminates at its upper end in an inwardly directed annular nozzle-like gap 9. At its lower end, openings 7 lead to the interior of the tube 4. Tube 4 at its lower end is closed by the metallic sleeve 10 and a flange screwed thereto which comprises a terminal or point of current supply 11.

Upper housing 1 has an insert defining a central pin 12 and a surrounding nozzle body 13. Pin 12 and body 13 serve as stationary current conductors or contact pieces as well as for guiding the gas flow. On body 13 is seated the laminated contact piece 14 which in the on-state of the switch establishes a metallic connection with the movable contact piece 15 on the movable switch rod 16. The movable contact piece includes also a central part 17 which is positioned in body 13 in the switch-on state without, however, carrying any substantial current on account of the great contact resistance. At the rear end of the movable contact piece is a piston-defining formation 21. The structure defined by tubes 4, 5, 6 serves as a cylinder within which the piston 21 moves. This cylinder is filled with quenching fluid. From rod 16, the electric current is conducted through the second laminated contact piece 18 and the intermediate piece 19 to the lower current terminal 11. In a housing 20 is disposed the mechanism for moving rod 16, which may comprise any suitable means. Upper housing 1 is suitably formed as a buffer chamber or may contain dampers or gas separators of known type.

In FIG. 2, contact head 15 with its pistonlike lug 21 has been moved slightly out of the switch-on position. An arc 24 has been formed between head 15 and a lamination of contact piece 14. Further, the descending piston 21 has displaced quenching fluid. At the beginning of the movement of the piston in switch-opening direction there is the possibility that quenching fluid will flow over the piston 21 laterally and escape along pin 17 through the nozzle opening 22. In the position shown, the piston has

just closed the annular flow-in space 23. On the other hand, gap 9 has just been uncovered by the upper edge of head 15. Piston 21 thus moves the fluid behind it through the openings 7 (FIG. 1) into the channels 8, whence it flows in a directed beam from gap 9. The short arc 24 thereby is forced to form a loop which finally contacts body 13 so that a new arc base is established there, while the arc base on one of the laminations 14 is extinguished. Also, the arc base of the movable contact piece changes, under the action of this fluid current, from the upper rim of head 15 to the burning tip 17. In this manner, the two contact functions, namely constant current contact and arc contact, may be carried out separately and by means of different materials. During the further descent of head 15, piston 21 continues to move the fluid through the channels 8 and gap 9, and the fluid escapes through body 13. The arc base is thus shifted into the interior of nozzle 13, the extent of such travel depending on the flow intensity. In order to avoid, in the case of very pronounced fluid currents such as short-circuit disconnections resulting from a heavy current produced by the arc itself, any unnecessarily great extension of the arc in its travel, a limiting pin 12 (FIG. 1) may be provided. The nozzle 13 has the particularly important function of screening the hot spot at the arc base (which still emits electrons long after the arc has been extinguished), with the aid of the advanced cold nozzle rim.

After having moved a certain distance, contact head 15 reaches the position shown in FIG. 3. It will be noted that the interior of the cylinder is provided with annular recesses exemplified by the region designated 23. These recesses are more closely spaced in the region occupied by the piston 21 during the initial portion of its stroke than in the region occupied by the piston during the later portion of its travel. As a result, the contact between the piston and the cylinder is greater during the initial portion of its stroke than later, whereby less fluid travels past the piston during the earlier part of the piston travel.

In FIG. 3, piston 21 has just left the portion of the interior insulating tube 6 which has the more closely spaced recesses, and now laterally uncovers a much longer annular space. The fluid from the space below the piston thus can more freely flow around the piston in the axial direction of the cylinder, and thus flow directly along pin 17. The cross-sections of the openings in the piston and those of the channels 8 and of the gap 9 are so graded that the fluid current which previously flowed through the channels 8 now follows both paths and is divided in a predetermined ratio. The result is that the interior space about the arc which previously had been washed only to a limited extent, now is intensively washed in the vicinity of the quenching position, and the arc column is thus cooled. The fluid flow about pin 17 which still continues after the arc has been extinguished, electrically screens the emitting hot spot left there from the switching path. For similar reasons, provision also has been made that the flow from gap 9 ceases only when the switching path has again been sufficiently consolidated electrically. Such flow of fresh fluid well insulates or screens the upper fixed contact pieces.

In the example shown in FIG. 4, tubular stationary contacts 25, 26 are provided in place of the laminated contact pieces 14, 13 of FIGS. 1 to 3, and the movable contact head as well as the switch rod is formed as a tubular contact piece 27. Pin 17 corresponds to the former design. While in the former example, however, the piston producing the quenching fluid flow was an integral part of the reciprocable switch rod, a fixed piston 28 is used here. It is, however, also possible to use a piston which is driven in the opposite direction by the contact tube, for example by means of any suitable reversing gear. The other structural components correspond to those of FIG. 1, and the mode of operation of the example shown in FIG. 4 is as follows:

As soon as contact tube 27 through any suitable driv-

ing mechanism (not shown) is moved downwardly from the switch-on position, it displaces fluid from its interior due to the action of fixed piston 28, and the fluid flows along pin 17. The fluid present in the space between tube 6 and tube 27 is forced by a collar 29 on the outside of tube 27, which collar slides snugly in tube 6, through the openings 7, channels 8 and gap 9 past nozzle contact 13 and through the opening in the latter into the buffer chamber 30. Further, when contact tube 27 moves into the drive housing 20, the fluid present in the latter is displaced and flows through compensating bores 31, the openings 7, channels 8 and gap 9 to the fixed contact pieces 13 and 25.

In the example shown in FIG. 5, 3 again is the metallic flange which holds the exterior insulating tube 4. The intermediate insulating tube 5, the interior insulating tube 6 and gap 9 formed by the two tubes correspond to the parts of FIG. 1. The nozzle body 13 is practically unchanged in its outside dimensions. Additionally, however, bores 32 have been provided in its upper portion, while the lower portion is formed as a sliding contact piece. The latter may be of any suitable nozzle-like construction. In the drawing, contact piece 33 is a slotted piece of tube with an annular ring 34. In the switch-on position, the exterior tubular contact piece 25 as well as the interior nozzle contact-piece 33 are in metallic contact with the movable contact counterpieces 17 and 15 or 27. It is of advantage to so form the contact pieces that the inner pair of contact pieces 33, 17 is separated last during the switch-off procedure. The holes 32 serve to enhance the fluid flow. Since the cross-section of the openings in the nozzle contact piece 33 possibly may not suffice for the quick discharge of fluid, additional venting means may be provided by increasing the number of bores 32.

In the form of invention shown in FIG. 6, a cap 35 having a central bore 36 is movable in contact tube 27. The lower edge of the cap is provided with a plurality of openings 37. The position shown corresponds to the position of contact tube 27 at the end of the switch-off movement. A bottom lug 38 of contact pin 17 has entered a damping bore of fixed piston 28. Bores 40 disposed laterally of pin 17 serve for letting quenching fluid flow from the space above piston 28. During the switch-off movement, the displaced fluid flows through the bores 40 along pin 17 and through bore 36 of cap 35 into the quenching space. The openings 37 are closed by a bulge 41 on contact tube 27. These openings serve for providing, during the switching-on movement, a possibility or reverse flow for the fluid present in front of cap 35, as then bore 36 in depressed cap 35 is fully occupied and closed by pin 17. The collar 29 provided on contact tube 27 again produces, during the switch-off movement, the second fluid current through the openings 7, channels 8 and gap 9 to the fixed contact pieces. The compensating bores 31 in the lower metallic body 10 allow the fluid to balance its pressure in the channels 8 and the drive housing 20.

What I claim as new and desire to secure by Letters Patent, is:

An electric switch including stationary and movable contact pieces and arc-quenching means, each of said contact pieces comprising a central arc-carrying contact and an annular current-carrying contact surrounding and spaced from said central contact; said current-carrying contacts being adapted to engage to close the switch and to disengage to open the switch, disengagement of said current-carrying contacts engendering an arc between them; said arc-quenching means including an annular nozzle surrounding said current-carrying contacts, means for directing a fluid blast through said nozzle toward the interior of said annular contacts in order to shift the arc from said current-carrying contacts to said arc-carrying contacts, and means for directing a fluid blast along the axis of said current-carrying contacts after said nozzle-directed blast has been effective long enough to shift the arc, said

fluid-directing means including a piston movable with said movable contact piece and a cylinder within which said piston moves, the interior surface of the cylinder having annular recesses so spaced that during the initial portion of the piston stroke in the direction of switch opening the contact between the piston and cylinder is greater than during the later portion of the piston stroke, said cylinder being filled with quenching fluid and being provided with a communication between the region behind the piston and said annular nozzle, whereby the blast created during said initial portion of piston travel is directed mainly through said communication while the blast created during the later portion of piston travel is mainly past said piston in the axial direction of the cylinder.
